LAMP HOUSING FOR HIGH INTENSITY READING OR WORK

Warren C. Portman, Peekskill, and Alex J. Weinstein,
Croton-on-Hudson, N.Y., assignors to The Ednalite
Corporation, Peekskill, N.Y., a corporation of New
York

Filed Oct. 29, 1968, Ser. No. 14,221

Term of patent 14 years

Int. Cl. D26—02

U.S. Cl. D48—20

Fig. 1.

Fig. 3.

Fig. 4.

Fig. 5.

Fig. 2.

FIG. 1 is a perspective view showing the design of a lamp housing according to this invention, with a portion of a support therefor being shown in broken lines;

FIG. 2 is a side elevational view;

FIG. 3 is a top plan view;

FIG. 4 is a front elevational view; and

FIG. 5 is a back elevational view.

The support is fragmentarily shown in broken lines in FIG. 1 for illustrative purposes only.

We claim:

The ornamental design for a lamp housing for high intensity reading or work, substantially as shown and described.
